UNITED STATES PATENT OFFICE.

SIDNEY O. COWLES, OF SALISBURY, CONNECTICUT.

JAR AND CAN OPENER.

Application filed May 7, 1924. Serial No. 711,727.

To all whom it may concern:

Be it known that I, SIDNEY O. COWLES, a citizen of the United States, and a resident of Salisbury, in the county of Litchfield and 5 State of Connecticut, have invented a new and Improved Jar and Can Opener, of which the following is a specification.

My invention relates to a device employed more especially for opening cans having different forms of closures, and an object of 10 my invention, among others, is to provide a can opener that may be employed for opening cans of different structures; and a further object of the invention is to provide a 15 can opener that shall be simple in construction, particularly efficient in operation, and one that may be produced at a minimum cost.

One form of can opener embodying my 20 invention and in the construction and use of which the objects herein set out, as well as others, may be attained, is illustrated in the accompanying drawings, in which—

Figure 1 is a side view of my improved 25 jar and can opener illustrating its manner of use;

Fig. 2 is a top view of my improved jar and can opener shown in its closed condition, and

Fig. 3 is a side view of the upper portion 30 of a fruit jar illustrating the method of operation of the tool.

One form of fruit jars in common use at the present time embodies a glass structure 35 with a cover that is held in place by a clamp, a rubber gasket being placed between the cover and mouth of the jar. After the contents of such a jar have been sealed, the cover and gasket are caused to adhere so closely to the mouth of the jar as to require 40 considerable force to release the cover. My improved jar opener herein illustrated and described embodies means that are particularly efficient for admitting air underneath 45 the cover to the jar, thereby removing the vacuum and enabling the cover to be loosened, one of the elements entering into the tool for performing this operation also serving a purpose for opening cans of other construction.

In the accompanying drawings the numeral 5 indicates the handle of my improved tool that is preferably constructed of sheet metal, of substantially oval form, providing 55 an opening into which a corkscrew 6 may be folded, the end of the corkscrew being

pivots attached to the side parts 8 of the handle that are brought close together at this point. The side parts 8 beyond such pivot are brought still closer together and a 60 can opener blade 9 is secured between said side parts at this point, and beyond this point said side parts are closed together and firmly secured as by riveting. The term 65 “can opener blade” is employed herein to indicate the common form of blade having a point to be forced through the metal of the can top and a cutting edge to cut a slit in the metal from the point of piercing.

A venting blade 10 is pivotally mounted 70 upon a stud 11, this being a screw stud as herein shown, and this stud also forms one element in securing the blade 9 to the handle. The venting blade 10 is offset from the pivot 75 and its extreme end is also formed as a bow 12 to fit the end of the handle 5. This end of the blade 10 is formed into a penetrating 80 edge 13 and is spaced from the main part of the blade which is adapted, in the use of the tool, to penetrate between the gasket 14 of 85 a cover and the lip 15 formed at the mouth opening of the jar 16.

In the use of the tool thus far described 90 the blade 10, by a swinging movement in a plane parallel with the plane of the blade 9, is extended as illustrated in the dotted lines in Fig. 1, and the edge 13 of the blade 95 is inserted between the gasket 14 and the lip 15, as shown in Fig. 3. The sharpened edge 17 of the blade 9 is placed between the gasket 14 and the lip 15 on the opposite side 100 of the jar cover 18, as illustrated in Fig. 1, and the handle 5 is then swung in the direction indicated by the arrow in Fig. 1. This causes the sharpened edge 17 of the blade 9 and the penetrating edge 13 of the blade 10 to be forced between the gasket 14 and the lip 15, thereby providing an opening to admit of the entrance of air into the jar, thus 105 eliminating the vacuum and loosening the cover of the jar, and enabling it to be readily removed.

The blade 9 is secured by the screw stud 11 and also by a rivet 19, the can opener comprising the handle 5 and blade 9 being of old 110 and well-known construction except as to the sharpened edge 17 on the back of the blade 9, this tool being provided with the usual fulcrum lips 20 common to can openers of this class.

In adapting this tool to my present purpose I use the blade 9 in connection with the

blade 10 as a penetrating tool for glass jars, and the blade 9, when the blade 10 is folded against the handle, may be used in the ordinary manner. The blade 9 is provided with 5 the usual sharpened front edge 21, terminating in a piercing point 22, and I have provided this blade with the sharpened edge 17 that, in addition to the functions hereinabove described in connection with the blade 10, serves a useful purpose in the opening of 10 ordinary tin cans, as this sharpened edge 17 makes the operation of cutting out the end of an ordinary tin can much easier than is the case with the usual form of can opener 15 of this type as both edges perform a cutting operation, and the edge 17 does not, therefore, have the resistance to penetration of the blade that it would have if it were blunt or square.

20 In accordance with the provisions of the patent statutes I have described the principles of operation of my invention, together with the device which I now consider to represent the best embodiment thereof; but 25 I desire to have it understood that the device shown is only illustrative and that the invention may be carried out by other means and applied to uses other than those above set out.

30 I claim—

1. A jar and can opener comprising a handle with a can-opener blade secured thereto, means cooperating with said blade to open a can by a cutting operation, and a penetrator blade extending from said handle and having a penetrating edge spaced from the can-opener blade for the purpose of receiving the end of a jar between said blades.

40 2. A jar and can opener comprising a handle with a can-opener blade secured thereto, means cooperating with said blade to open a can by a cutting operation, a penetrator blade extending from said handle and having a sharpened end spaced from the main 45 part of the blade, said sharpened end being spaced from the can-opener blade to receive the end of a jar between them.

3. A jar and can opener comprising a handle with a can-opener blade extending therefrom, means cooperating with said blade to

open a can by a cutting operation, and a penetrating blade pivotally attached to said handle and having a sharpened end spaced from the can-opener blade to receive the end of a jar between them.

4. A jar and can opener comprising a handle with a can-opener blade extending therefrom, and adapted to serve a function in connection with different can-opening elements, and a penetrating blade having its end bent to conform to the shape of the handle to overlap the end thereof and comprising a portion of a handle in one use of said blade as a can opener, the end of the penetrating blade being sharpened and adapted to be spaced from the can-opener blade for the reception of the end of a jar between said blades in another use of the can-opener blade as a can opener.

5. A jar and can opener comprising a handle, a can-opener blade secured to and projecting from the handle, said blade having a piercing point, and a sharpened edge on both its front and rear edges, and means to cooperate with said blade to force it laterally between the cover and the edge of the mouth of a jar.

6. A jar and can opener comprising a handle terminating in fulcrum lips, a penetrator blade pivotally secured to the handle and having a sharpened penetrating end, and a second blade secured to said handle to lie between said lips and said penetrator blade in its extended position, said second blade cooperating with said lips and said penetrator blade for opening cans by different operations.

7. A jar and can opener comprising a handle with a blade secured thereto, and a penetrator blade extending therefrom and having its end bent to fit the end of said handle to constitute a portion of a handle in one use of the device as a can opener, said bent end being formed with a penetrating edge spaced from the first-mentioned blade for the purpose of receiving the end of a jar between said blades, said penetrating blade having a swinging movement in a plane parallel with the plane of the first-mentioned blade.

SIDNEY O. COWLES.
